UNITED STATES PATENT OFFICE.

CLEMENT F. STREET, OF SCHENECTADY, NEW YORK, ASSIGNOR TO THE LOCOMOTIVE STOKER COMPANY, OF WILMERDING, PENNSYLVANIA, A CORPORATION OF PENNSYLVANIA.

FUEL-DISTRIBUTER FOR FURNACES.

1,195,531.

Specification of Letters Patent. Patented Aug. 22, 1916.

Application filed January 12, 1912. Serial No. 670,858.

To all whom it may concern:

Be it known that I, CLEMENT F. STREET, a citizen of the United States, residing at Schenectady, in the county of Schenectady 5 and State of New York, have invented new and useful Improvements in Fuel-Distributors for Furnaces, of which the following is a specification.

This invention relates to fuel distributors 10 for furnaces, and more particularly to mechanical stokers for locomotive boiler furnaces in which the fuel is fed through the distributors by means of a blast or jet of steam or other fluid under pressure, as set 15 forth in my prior applications Ser. No. 565579, filed June 7, 1910, and Ser. No. 652,462, filed October 2, 1911.

One of the objects of my present invention 20 is to provide an improved detachable distributor end which may be attached within the fire box to the body portion or shank extending through the opening in the furnace wall; and another object is to provide an improved form of connection, having interlocking projections, between the parts 25 whereby the flaring distributor end may be retained in its position by gravity and inclined at any desired angle, and be readily detached and renewed when necessary.

30 In the accompanying drawings: Figure 1 is a plan of one form of my improved distributor, adapted to be used at the side of the furnace; Fig. 2, a side elevation of the same; Fig. 3, an end elevation of the detachable hood or end of the distributor; Fig. 4, a plan of a slightly modified form of my improved distributor adapted for use at the center or intermediate portion of the furnace; Fig. 5, a side elevation of the same; 35 Fig. 6, an end elevation of the hood; and Fig. 7, an end view of the shank with the hood removed.

According to the construction shown in 40 Figs. 1, 2, and 3, my improved distributor comprises an elbow portion, 19^a, having a flanged opening for connection with a fuel pipe, 19^b, an air inlet, 27, a steam blast connection, 28, and provided with a substantially cylindrical shank, 19, extending 45 through an opening, 21, in the furnace wall.

At the end of the shank within the fire box, the flaring distributor end, 23, is mounted by detachable connections. One form of such connections may comprise one or more

notches or openings, 32, formed in the shank 55 portion, and corresponding hook-shaped projections, 33, formed on the distributor end, these parts being adapted to interlock whereby the hood is retained in its position by gravity and both parts being provided 60 with abutting flanges, 34 and 35, which rest one upon the other, and support the distributor end at the desired elevation. By varying the angle of these engaging flanges, the distributor may be elevated at different 65 angles of inclination to suit any and all conditions of service.

For use as a side distributor, the detachable end, 23, may be formed as a broad flaring hood having a slightly curved under surface and short depending flanges, 25, at its side edges, and the bottom portion of the shank, 19, may be provided with a wedge shaped projection, 24, at its ends for diverting the fuel upward against the under face 75 of the detachable hood. A flange, 30, may be formed on the elbow for engaging the front face of the the boiler shell.

As shown in Figs. 4 to 6 of the drawings, 80 the distributor is of the same general construction, but the elbow, 20^a, with its shank portion, 20, is shown tapered, toward the bottom and provided with segmental ribs or flanges, 31, for fitting the cylindrical opening, 21, through the furnace wall of the 85 boiler. This construction brings the side walls closer to the line of the fluid pressure blast, and is better adapted for handling finely divided fuel. The detachable distributor end or hood, 23^a, as shown in this design, is formed with flaring wings curved 90 outward and downwardly to a point below the end of the shank, the wings being divided by a curved central rib, 36. For the purpose of connecting this form of hood 95 with the shank portion of the distributor, the latter is provided with side notches, 37, in the end flange, while the hood portion has projections, 38, for engaging in said notches 100 when the hood is slipped down over the end of the shank. The shank portion of the elbow may also be provided with an inside longitudinal rib, 40, arranged in line with the central rib, 36, of the hood.

By means of my improvement in which 105 the distributor end or hood is separate and detachable from the other portion, said distributor end may be made of a different ma-

terial, which is better adapted to withstand the excessive heat to which the same is subjected within the furnace.

The distributer end or hood may also be mounted at any desired angle of elevation and may be readily detached and renewed or replaced whenever necessary or desired.

As the hood is retained in its place upon the end of the shank merely by its own 10 weight, no tools or other parts are necessary in making renewals, the worn out hood being simply lifted off from the end of the shank, and the new one put in its place.

Having now described my invention, 15 what I claim as new, and desire to secure by Letters Patent, is:—

In a mechanical stoker, the combination

with a furnace wall having an opening, of an elbow outside the wall provided with fuel and fluid pressure connections and having 20 an integral tubular shank extending through and closely fitting said opening, and a flaring distributing hood within the furnace, said hood and the end of said shank having interlocking notches and projections for detachably connecting the hood with said shank and retaining the same in position by gravity.

In testimony whereof I have hereunto set my hand.

CLEMENT F. STREET.
